UNITED STATES PATENT OFFICE.

HENRY C. WELLE, OF CROCKETT, CALIFORNIA.

METHOD OF TREATING SUGAR.

No Drawing.

Application filed October 1, 1923. Serial No. 665,949.

This invention relates to the treatment of sugars and particularly to the treatment of soft sugars (commonly known as yellow or brown sugars) such as are produced by sugar refiners to be used for direct consumption, for baking and for cooking.

The process of making soft sugars at the present time varies considerably in different refineries, but the practice which has heretofore been used may in general be stated to be somewhat as follows:

For a base, impure sugar liquors or syrups such as syrups from granulated sugars, or raw affination or wash syrup or the regular granulated sugar liquors from the char filters may be used. These bases are generally selected so as to have a purity between 75° and 88°, the exact purity depending on the type of material used and the type of sugar produced. This product is generally, but not always, given a special char filtration, the extent of this depending on the base selected, the color desired in the product produced, and other considerations. For example, if a syrup from granulated sugar is used as a base it will need relatively little or even no char filtration, as the liquor from which it was originally produced has already had considerable char filtration. On the other hand, where such dark material as affination syrup is used it will require considerable char filtration in order to produce the required color.

After char filtration the material is sent to the pan floor to be boiled in the vacuum pans. Here the material may be boiled direct or may be boiled with syrups returned from previous strikes, depending on the color of sugar that is desired.

After boiling, the massecuite is spun out in such a way that a small amount of syrup is left adhering to the sugar so as to give it the desired color and flavor. The sugar is then generally given a certain amount of aeration and packed for shipment.

It will be understood that there are a great many modifications of the above practice used by different refiners, but the above outline will approximately cover most of the methods heretofore in use.

In producing these soft sugars it is desired that they have a bright, clear, yellow-golden color that will not change on storage. However, in practice, it is found that the sugars produced by the above practice often have a dull, dirty appearance, the extent of

this varying considerably. Even if originally produced with a fair color, it frequently happens that a dark dirty color is gradually developed on storage. It is the principal object of the present invention to so produce a soft sugar as to insure that it will acquire and maintain a desirable color.

Investigation has indicated that this difficulty with the color is due to the presence of iron compounds, probably iron polyphenols. These compounds are probably formed in the various operations in the refinery, through some of them may be present in the original raw sugars. As these iron polyphenols are very dark in color, a small quantity of them will greatly modify the appearance of the sugar. It is believed that the ferric forms are much darker than the ferrous forms, therefore the development of this dark color on standing is believed to be due to oxidation.

It has been found that by the use of solutions containing phosphate ions (that is, PO_4 anions) this dark coloring matter can be broken up. This is done by the application of solutions of phosphoric acid or phosphate salts, the iron polyphenols being decomposed with the precipitation of iron phosphate and the liberation of free polyphenols. While these free polyphenols possess a certain amount of color, it is not objectionable—in fact is probably a desirable coloring matter to have in the sugar. The iron phosphate is light in color and so produces no harmful effect on the color of the sugar.

In practice the phosphoric acid or phosphate salts may be applied in several different ways. It is found that the most satisfactory point in the process at which to apply the phosphoric oxide salts to the sugar is in the centrifugals after the bulk of the adhering syrup has been spun off, or to the sugar after it has left the centrifugals.

The actual application of phosphoric acid or phosphoric acid salts may be carried on as follows: A solution is made up containing twenty per cent phosphoric acid, (H_3PO_4) or its P_2O_5 equivalent in acid calcium phosphate, acid sodium phosphate or other common phosphate salts, (it being preferable to use them in the acid form). This is added to the sugar centrifugal just before or just as it is being emptied, in such quantities as will give about 0.1 per cent of H_3PO_4 on the weight of sugar in the centrifugal. If the material is added with a cup, it is thrown

into the basket of the centrifugal just before the brake is applied. This results in a slight washing of a small portion of the sugar, but in being plowed out and passing through the sugar scrolls the material is thoroughly mixed so that there is no evidence of washing of the sugar, and the entire mass of sugar becomes treated with the phosphoric acid. If the material is applied with a spray, it is preferable to apply it while the sugar is being plowed out or in the scroll beneath the centrifugals.

As an example, when forty inch centrifugals holding 400 pounds of sugar are used, 15 two pounds (for approximate work one quart is used) of the prepared solution are thrown on the sugar just before the brake is applied to the centrifugal. If the centrifugal holds only 350 pounds of sugar (as is the case with some grades) a smaller quantity of 20 solution may be used, or the solution may be made more dilute—about 17.5 per cent. It will be found that the added water in the sugar does no harm for ordinary grades of 25 sugar. After dropping out of the centrifugal the sugar is passed through scrolls that mix it thoroughly and then through an aerating device such as is commonly used for handling soft sugars.

20 When the phosphoric acid is added it is found that there is a liberation of acetic and other volatile acids, due to the presence of their salts in the sugar. If the sugar is thoroughly aerated while warm these acids are 25 practically all volatilized and the sugar becomes as alkaline or even more alkaline than before treatment. If not aerated there will be an acidity to the sugar that can be readily detected by tests, though the odor of volatile acids may not be very evident when the sugar is cold. I therefore prefer to give the sugar as thorough an aeration as possible.

40 While it is stated that 0.1 per cent of phosphoric acid (H_3PO_4) on the weight of the sugar should be applied, this is only an ap-

proximate figure and the desired quantity may vary greatly with the circumstances. It is found that if straight phosphoric acid is used, a smaller quantity will suffice than if phosphoric acid salts are used, and also 50 with light colored sugars a smaller quantity of material may be used than with dark colored sugars. In some cases, with light colored sugars and where a solution of straight phosphoric acid is used, as little as .02 per cent to .03 per cent H_3PO_4 on the weight of sugar will suffice, and in other cases with dark colored sugars, it may be necessary to add 0.2 per cent H_3PO_4 or its equivalent in phosphoric acid salts. 55

60 While phosphoric acid alone is somewhat more effective than the acid salts, the latter have the advantages that they are somewhat easier to handle and the generation of volatile acids is somewhat less.

65 Having thus described my invention, what I claim and desire to secure by Letters Patent is:

1. The process of adding small quantities of a solution containing phosphate ions to 70 soft sugar not in solution, and thoroughly mixing the sugar with the solution to obtain a uniform mixture.

2. The process of adding small quantities of a solution containing phosphate ions to 75 soft sugar, thoroughly mixing the sugar and aerating same sufficiently to remove the volatile acid developed.

3. The process of refining sugar which consists in adding small quantities of a solution containing phosphate ions to soft sugar after the surplus syrup has been removed, and thoroughly mixing the sugar and phosphate solution.

4. The process of adding small quantities of a solution containing phosphate ions to soft sugar, after the surplus syrup has been spun off by centrifuging, and thoroughly mixing the sugar and the solution.

HENRY C. WELLE.
